UNITED STATES PATENT OFFICE

2,045,879

AUXILIARY COMPARTMENT FOR
REFRIGERATOR DOORS

Abraham S. Shafer, Philadelphia, Pa.

Application October 1, 1934, Serial No. 746,461

3 Claims. (Cl. 20—35)

This invention relates to an improved auxiliary compartment for refrigerator doors, it being obvious that there may be one or a plurality of such compartments, and the purpose of the invention

5 is to provide such compartment with a sliding panel in the front of the refrigerator door to permit access to the compartment, for the removal of a product or article of food without opening the main door of the refrigerator.

10 Another purpose of the invention is to provide a compartment of this kind having its rear interior wall provided with a panel opening and a pair of sliding panels therein, so that when the front panel is opened, the two panels for the rear 15 wall of the compartment may automatically close, thereby preventing escape of the cold air from the interior of the refrigerator, likewise preventing warm air entering the interior of the refrigerator, and when the front panel is closed, the rear panels 20 are opened, thereby allowing the cold air to enter the compartment to retain the latter at the same temperature as the interior of the refrigerator.

Another purpose is to provide a device of this kind, wherein it is possible to provide the door 25 with as many compartments of this character as may be mounted on the door without inconveniencing the rest of the refrigerator as such, and thereby reducing the opening of the door to a minimum.

30 A further purpose of the invention is to provide a refrigerator main door having a plurality of auxiliary compartments provided at the front and rear thereof, with sliding air tight panels or leaves, which may be constructed of any suitable material 35 preferably metal porcelain finished, or heavy shatter proof glass, or polished wire glass set in a chromium frame, and in this latter instance visibility into the compartment is possible, in order to show the contents of the compartments.

40 A still further purpose of this invention is to provide a refrigerator, the main door of which may be kept closed substantially most of the time, since the auxiliary compartment or compartments will eliminate the necessity of frequently opening 45 the main door. The only time the main door is required to be open is when placing in the main compartment of the refrigerator or removing therefrom large articles of food and the like.

By keeping the main door closed most of the 50 time the loss of cold air may be reduced at least fifty percent, thereby greatly conserving on the various refrigerator elements, as well as reducing the operating cost in proportion.

It is to be understood that the particulars herein given are in no way limitative, and that while

still keeping within the scope of the invention, any desired modification of details and proportions may be made in the construction of the appliance according to circumstances.

The invention comprises further features and 5 combination of parts to be hereinafter set forth, shown in the drawing and claimed.

In the drawing:—

Figure 1 is a view in elevation of a conventional type of refrigerator showing the main door provided with a plurality of sliding airtight panels or leaves for closing panel openings, through which access may be had to the several compartments.

Figure 2 is a vertical sectional view through Figure 1 on line 2—2 thereof, showing one of the 15 outside paneled openings closed and rear sliding airtight panels open.

Figure 3 is a cross sectional view on line 3—3 of Figure 2.

Figure 4 is a sectional view through a portion 20 of the door and through one of the auxiliary compartments showing two panels, one in front of the door and one closing the back part of the compartment with a modified construction of connections between the panels.

Referring to the drawing 1 identifies a cabinet of a refrigerator, which may be of the ordinary type, wherein manufactured ice may be used for chilling the interior of the main chamber of the cabinet, or may be of the electrical type. In 30 either case it is unnecessary to show the chilling coil unit or the ordinary ice chamber. The cabinet is provided with a main door 2, the opening of which will permit access into the chamber 3 where foodstuffs are stored. Carried by the 35 door 2 is a plurality of auxiliary compartments 4, which are constructed by providing a plurality of auxiliary compartment walls 5. The door 2 has a plurality of panel receiving openings 6 provided with guides 7 in which the panels 8 are guided. The guides 7 connect with passageways 9 in the wall of the door to permit the panels 8 to enter therein when raised. The wall 5 of each compartment 4 has a panel receiving opening 10 provided with guides 11 in their vertical edges, for the reception of the upper and lower panels 12 and 13. The lower edge of the panel 12 has a tongue 14 to receive a packing 15 in the upper edge of the panel 13, so as to make an airtight fitting joint between the two panels. 50 The wall 5 has a passageway 16 into which the panel 12 moves when raised, while the lower portion of the wall 5 has a passageway 17 into which the lower panel 13 enters when lowered. The bottom of the compartment 4 has a passage 18

55

through which catgut cords or cables may pass when operating both sets of panels front and rear. A catgut cord or cable 19 is connected at 20 to the upper panel 12 and passes over pulleys 21 and in turn is connected at 22 to the panel 8. A catgut cord 23 is connected at 24 to the lower edge of the panel 8 and is passed over the pulley 25, through the passage 18 and over a pulley 26 and up through the guide 11 and is connected at 10 27 to the panel 12. Obviously when the panel 8 is raised by engaging the fingers in the recess 28 the cord 23 is moved in the direction of the arrow a, which will lower the panel 12 to a closed position in the panel receiving opening 10. A 15 catgut cord 29 is connected at 30 to the cord 23 and passes over a pulley 31 and is connected at 32 to the lower portion of the panel 13 so that when the cord 23 is operated in the direction of the arrow a the cord 29 likewise operates and closes 20 the panel 13.

When the panel 8, after it is raised, is again lowered the cord 19 is pulled in the direction of the arrow b', which will raise panel 12. A catgut cord 33 is also connected at 27 to the panel 12, passes downwardly through the guide 11 over a pulley 34 in the lower part of the wall 5 and in turn is also connected at 32 to the panel 13. When the panel 12 is raised the cord 33 is operated in the direction of the arrow c, therefore pulled downwardly on the panel 13, opening same simultaneously with the opening of the panel 12.

Obviously when the panel 8 is in an open position the panels 12 and 13 are in closed position and when the panel 8 is in a closed position the panels 12 and 13 are in open positions. In this way warm air when the panel 8 is open is prevented from entering the chamber 3 at the same time preventing the escape of cold air from the chamber 3. Also obviously when the panel 8 is closed and the panels 12 and 13 are open the cold air in the chamber 3 can enter the compartment 4.

Referring to Figure 4 it is obvious that there is disclosed a modification of the auxiliary compartment, wherein the compartment is of the same shape as that in the other figures, the walls of the compartment having the same guides as in Figure 2. Instead of two panels at the rear of the compartment only one panel 12a is shown, one end of which is connected by a cord 35 to the upper edge of the front panel 8a, the cord 35 passing over a pulley 36, the other end of the panel 12a has attached thereto a cord 23a, which in turn passes over pulleys 37 and 38 and connected at 39 to the lower edge of the panel 8a. These panels operate in guides 11a and 11b, while a cord 23a passes through a passage 39a. It is obvious that by moving the panel 8a, engaging the fingers in the recess 8b the panel 12a will be lowered, shutting off the escape of cold air from the interior of the cold air chamber of the refrigerator, and allowing the contents of the compartment to be removed. On reverse move-

ment of the panel 8a the compartment will be closed against access thereto from the exterior, and the panel 12a will open, allowing cold air from the cold air compartment to enter the auxiliary compartment in the door.

It is obvious that there may be any number of auxiliary compartments that can be conveniently formed in the main door of the refrigerator. Also it is obvious that the walls of these compartments may be constructed of any suitable metal either enameled, or they may be constructed of porcelain. Also the main door is hollow and contains packing as an insulation against radiation or escape of the cold air in the cold air chamber of the refrigerator or the penetration of exterior air in a room. Furthermore the panels for closing the openings in the main door may or may not have packing as identified at 8b, 12b and 13a, also as an insulation against radiation or escape of the cold air in the refrigerator as well as the penetration of exterior air.

The invention having been set forth, what is claimed is:

1. In a refrigerator door, a plurality of compartments extending therethrough and having openings in their front and rear walls, panels for closing said openings, guides in the sides of said openings with the panels slidably mounted therein, and means connecting the panels for moving the latter alternately to open and closed positions.

2. In a refrigerator door, a compartment extending therethrough, the front and rear wall of said compartment having openings therein, guides in the sides of the openings, upper and lower panels slidably mounted in the guides of the opening of the rear wall for movement toward and away from each other, a single panel in the guides of the opening of the front wall, and means connecting the rear panels with the front panel for operating the panels in unison and alternately to open and closed positions.

3. In a refrigerator door, a compartment extending therethrough and having openings in their front and rear walls, guides in the sides of said openings, upper and lower panels mounted for cooperation in the guides of the opening of the rear wall, a single panel in the guides of the opening of the front wall, and means for operating the single panel with respect to the upper and lower panels for alternately moving the panels to open and closed positions, said operating means comprising flexible means connecting the upper portion of the upper panel and the upper portion of the single panel, flexible means connecting the lower portion of the single panel and the lower portion of the upper panel, flexible means connected to the second flexible means and to the lower portion of the lower panel, an additional flexible means connecting the lower portion of the lower panel and the lower portion of the upper panel, and guide pulleys for the flexible means.

ABRAHAM S. SHAFER.
